UNITED STATES PATENT OFFICE.

WALTER S. PAINTER, OF NEW YORK, N. Y.

ERECTING MEANS FOR BUILDINGS OF SECTIONAL CONSTRUCTION.

1,369,295.

Specification of Letters Patent. Patented Feb. 22, 1921.

Application filed June 5, 1919. Serial No. 302,054.

To all whom it may concern:

Be it known that I, WALTER S. PAINTER, a subject of the King of Great Britain, residing in the borough of Manhattan, of the city of New York, in the State of New York, have invented certain new and useful Improvements in Erecting Means for Buildings of Sectional Construction, of which the following is a specification, reference being had 10 to the accompanying drawing, forming a part hereof.

This invention relates to erecting means of a semiportable character, adapted for use in handling building material, which means 15 can be quickly set up in operative condition at different building sites.

The object of the invention is to provide a means for quickly handling large building units and in particular to erect the buildings 20 constructed according to the application for Letters Patent filed by me as Serial No. 302,053 on June 5, 1919. The means employed is a system of trolleys traversing one another to handle material at all angles in 25 the manner hereinafter set forth.

In the preferred form trolley carrying cables or wires, supported by suitable posts are stretched or extended lengthwise of the building to be directly over the longitudinal 30 wall thereof; the expression lengthwise is used but the intention is to have the carrying cables placed in the direction of the greatest number of parallel walls, the arrangement being such that wall blocks or slabs may be 35 raised and carried directly to where they are to be located in the building, in exact relation to that which they occupy when located in permanent position, and also similarly raising and carrying floor blocks to be 40 seated on the tops of oppositely located wall blocks; two wall blocks and a floor block constituting a complete section of the building, or of a compartment thereof.

In the accompanying drawing, forming 45 part of this specification and to which I will now refer—

Figure 1 is a plan view of a building having three longitudinal walls, showing the improved trolley system in connection therewith.

Fig. 2 is a side elevation.

Fig. 3 is an end view, and

Fig. 4 illustrates a method of handling wall blocks.

55 In the figures, 5 designates the longitudinal walls and 5' the blocks forming the

same, 6 the transverse walls and 7 a floor of a building partly erected. At a distance beyond the ends of the longitudinal walls 5, and directly in line therewith, are set up 60 posts 8, 8' vertically held by stays and guide lines, as indicated at 9 and 9' which may be connected at their lower ends to base plates 10, 10', on which may be placed windlasses 65 as at 11 and 11'.

Trolley lines 12, generally arranged in pairs are supported on the posts 8 in line with the walls 5. These trolley cables are firmly anchored to the ground as indicated at 13, but any other method of anchoring 70 suitable for taking the overturning and to resist the resultant stress from the carrying of the load, will be employed under suitable conditions.

Suspended from the trolley lines 12 are 75 carriers 14, provided with means for raising and setting the wall blocks as shown in Fig. 4. A suitable arrangement there shown consists of screw threads on the top dowel pins 15 of the blocks 5', screw sockets 16 placed 80 thereon and adapted to be connected to the carriers 14. The carriers 14 are generally provided with adequate raising apparatus consisting of an endless chain 23 and a ratchet and pulley 22, thus permitting the 85 wall block 5' to be raised at any point over which the trolley operates. The windlass 11' controlling lines 26 operates as a means of retarding the trolley against excess speed, the cable naturally being lower at the center 90 than at the posts and the tendency being to ride toward the center of the cable. The windlass is placed as a retardant or as a means of drawing back the load in case of a wall block being drawn back to the point 95 of rest.

To provide means for handling the floor slab 17, transverse trolley beams 18, one for each division of the building are supported 100 at their ends by suitable carriers on the trolley cables 12, located over the opposite walls of each division. These carriers are also designed to carry units placed between the longitudinal cables. It will be noted that the transverse trolley beams 18 can be shifted 105 along the longitudinal trolley cables 12, and such beams 18 are in themselves trolley rails, having suitable tackle 19 depending therefrom for raising the floor blocks. With this arrangement the floor block can be raised 110 anywhere along the line of the longitudinal walls at any distance therefrom; 21 indicates

a hand controlling guide line. The windlass 11, controlling line 20, is placed as a retardant or as a means of drawing back the load in case of a floor slab being drawn back 5 to the point of rest.

The operation of necessity having to work from the front and rear toward the center can readily be worked by using the cables from both ends. Another transverse trolley 10 beam 24 extending laterally over and beyond the outer longitudinal walls 5 is also supported by the trolley cables 12 and is provided with means for operating a bucket 25 for raising mortar and other material and 15 conveying it to any part of the operation. These transverse trolleys can be stationary or they can be shifted by moving the supports along cable 12.

The building conventionally illustrated 20 may be of any character and for any purpose, as for instance it may represent a row of dwelling houses in course of erection, a salient feature of the construction being the formation of the walls and floors of 25 standardized concrete blocks, two wall blocks and a floor block forming a completed section of the building or of its rooms or compartments.

The exact relation of the various trolleys 30 need not be exactly as described as long as the system is maintained. The system will not only make practical the handling of large concrete blocks, but will also enable buildings, or rows of buildings to 35 be erected with a minimum of hand labor, and in point of time, far more speedily than has ever been done before.

It is contemplated to build the roof in 40 sections formed on the ground, and placed in position by the aerial cable lines in such fashion as to eliminate the necessity of labor other than the placing of the sections on the building.

With reference to the doors and windows 45 these will be erected in place as the erection proceeds. The doors and windows will have rabbeted jambs which will lock over the partitions. The door frames will be complete with jambs, heads and sills and the 50 doors hung in position and the frame braced to admit of ready handling during erection. We have referred to means for holding the cables and trolleys above the altitude of the walls; in a large building, 55 the posts for holding the trolley lines above the walls will be raised at the completion of each floor and located in the proper position on the floors already built.

I claim:

60 1. An erecting means for buildings, comprising a trolley system located in the plane of each of the longitudinal walls of the building, a trolley system traversing the first mentioned system, each system supporting carriers adapted to travel along the

trolley lines, such carriers having means for supporting and placing in position heavy and light building units.

2. An erecting means for buildings, comprising a trolley system located in the plane 70 of each of the longitudinal walls of the building, means for holding the trolley lines above the altitude of said walls, carriers adapted to travel along the trolley lines and provided with means for connection 75 with light and heavy building units, and means for raising the units and moving each carrier with its depending unit to situate it in the desired position.

3. An erecting means for buildings, comprising a trolley system located in the plane 80 of each of the longitudinal walls of the building, a trolley system supported by and traversing the first mentioned system, each system supporting carriers adapted to travel 85 along the trolley lines, such carriers having means for supporting and placing in position heavy and light building units.

4. An erecting means for buildings, comprising a trolley line located in the plane 90 of each of the longitudinal walls of the building, means for holding the trolley lines above the altitude of said walls, carriers adapted to travel along the trolley 95 lines and provided with means for connection to the upper ends of wall blocks and means for raising the blocks and moving each carrier with its depending block to situate the block in the longitudinal wall.

5. An erecting means for buildings, comprising a trolley line located in the plane 100 of each of the longitudinal walls of the building, means for holding the trolley lines above the altitude of said walls, other trolley members supported to travel on the 105 trolley cables over the walls of a longitudinal division of the building and provided with means for raising a floor block, in position it will occupy in the building and means for moving the trolleys to locate the 110 floor block to rest on the tops of previously situated wall blocks in the opposite walls of the division of the building.

6. An erecting means for buildings, comprising a trolley line composed of two horizontally arranged cables or wires located in the plane of each of the longitudinal walls of the building, means for holding the trolley lines above the altitude of said walls, carriers adapted to travel along the trolley 115 lines and provided with means for connection to the upper ends of wall blocks and means for raising the blocks and moving each carrier with its depending block to situate the block in the longitudinal wall. 120

7. An erecting means for buildings, comprising a trolley line located in the plane of each of the longitudinal walls of the building, means for holding the trolley lines above the altitude of said walls, other 125

trolley members supported to travel on the trolley cables over the walls of a longitudinal division of the building and provided with means for raising a floor block, 5 in position it will occupy in the building and means for moving the trolleys to locate the floor block to rest on the tops of previously situated wall blocks in the opposite walls of the division of the building, car-

riers adapted to travel along the trolley 10 lines and provided with means for connection to the upper ends of wall blocks and means for raising the blocks and moving each carrier with its depending block to situate the block in the longitudinal wall. 15

This specification signed this 28th day of May, A. D. 1919.

WALTER S. PAINTER.
